DESIGN FOR A CASING FOR A GRINDING MILL

John C. Kopf, New York, N. Y., assignor to Jabez
Burns & Sons, Inc., New York, N. Y., a corpo-
ration of New York

Application June 19, 1934, Serial No. 52,242

Term of patent 14 years

To all whom it may concern:

Be it known that I, John C. Kopf, a citizen of
the United States, residing at New York, in the
county of New York, State of New York, have in-
vented a new, original, and ornamental Design
for a Casing for a Grinding Mill, of which the
following is a specification, reference being had
to the accompanying drawing, forming part
thereof, in which:

Fig. 1 is a front elevation of a casing for a
grinding mill, showing my new design;

Fig. 2 is a top plan view thereof.

I claim:

The ornamental design for a casing for a grind-
ing mill substantially as shown.

JOHN C. KOPF.
